UNITED STATES PATENT OFFICE.

RAYMOND C. BENNER, OF FREMONT, OHIO, ASSIGNOR TO NATIONAL CARBON COMPANY, INC., A CORPORATION OF NEW YORK.

ELECTRIC BATTERY.

Application filed March 11, 1920. Serial No. 365,058.

To all whom it may concern:

Be it known that I, RAYMOND C. BENNER, a citizen of the United States, residing at Fremont, in the county of Sandusky and 5 State of Ohio, have invented certain new and useful Improvements in Electric Batteries, of which the following is a specification.

This invention relates to dry cells of the 10 deferred action type in which all of the necessary constituents are incorporated in the cell and combined in such cooperative relationship as to permit the cell to be made ready for action by a single manipulation. 15 Patent 1,289,433 to H. F. French illustrates a cell of this kind and in certain respects the present invention may be considered to be an improvement in certain structural features utilized therein. The present cell 20 resembles the structure shown in the patent, in utilizing a supply of activating material at the lower end of the mix, adapted to be forced into operative relationship to the electrode.

25 In this and similar types of cells, spacers have been considered necessary around the mix to prevent displacement of the bobbin. These spacers interfere with the passage of the activating material into the operative 30 position when the activating material is in the form of a relatively heavy paste, and may also result in non-uniform distribution of said material. In cells of this type a wet mix is desirable, but if spacers are used 35 it has been found that it is difficult to prevent electrolyte from creeping over the spacers to the zinc and producing corrosion.

One of the objects of the present invention is to eliminate the spacers and to provide 40 a construction in which substantially uniform resistance is offered to the flow of the activating material into the space provided for this purpose.

Another object of the invention is to provide 45 a simple, inexpensive receptacle for the activating material which is adapted to be readily adjusted longitudinally on a hollow zinc electrode, to activate the cell and to provide a closure for one end of the tubular zinc.

Another object of the invention is to facilitate the introduction of the paste by

utilizing short cups for closing the ends of a tubular zinc electrode.

5 A further object of the invention is to secure an end cup adapted to retain the activating substance and to be supported on the zinc tube in two positions corresponding to the inactive and active conditions.

Other improvements reside in the structural features hereafter described in connection with the drawings in which:

Fig. 1 illustrates a structure embodying the invention, the parts being shown in partial vertical cross section in their inactive 60 relationship.

Fig. 2 is a central vertical section of the cell shown in Fig. 1, illustrating the relationship of the parts when the cell is rendered active. 70

Fig. 3 is a similar section of a modification, the parts being shown in their inactive 75 positions.

Fig. 4 is a similar section of the cell of Fig. 3 after it has been rendered active.

Referring particularly to Figs. 1 and 2 of the drawings, 1 represents a tubular zinc electrode open at both ends and having a molded bobbin therein spaced therefrom, comprising preferably a moist depolarizing mix 2 of carbon, manganese dioxide, and if desired electrolyte, surrounding a central carbon electrode 3 projecting therefrom. A waterproof insulating disk 4' and a spacer 4" may be fitted around the carbon electrode above the mix as shown. To support the bobbin an insulating disk 4 is fitted in the zinc tube and a seal 5 is poured thereover between the upper end of the zinc tube and the projecting end of the carbon electrode. 90 As stated above, a relatively heavy paste cannot be uniformly and readily forced into the space between the mix and zinc tube if spacers are placed therebetween, and moreover, carbon electrode, zinc tube and mix 95 are not held together sufficiently rigidly to permit the spacers to be safely omitted in the ordinary construction when utilizing such heavy pastes. In accordance with the present invention, these several members 100 mentioned are interlocked, for example, by providing the zinc electrode with a circumferential flange or collar 6 projecting into the seal, and by irregularities or indenta-

tions on the surface of the carbon electrode, such as at a plurality of notches located at points 7 and 8 adjoining the seal and mix respectively. A disk 9 is provided at the 5 bottom of the mix to protect the lower edge. This construction enables the bobbin to be held securely in position without the use of spacers and the mix is also supported so that it is not displaced when the mix bobbin is 10 subsequently utilized as a plunger to displace activating material to activate the cell.

With the arrangement shown the activating material 10 preferably comprises a paste of flour, starch, etc., and water or electrolyte 15 solution which is placed in a short waterproof cup 11. Although the construction is adaptable to activating substances of different consistency, it is especially useful in connection with relatively heavy pastes for 20 the reasons previously set forth. A protective covering for the activating material is desirable, especially with rather fluid materials, and for this purpose, I find an insulating disk 12 and a seal 13 are satisfactory for retaining the material and preventing evaporation of moisture from the activating material. A seal of the character described can be readily sheared from the cup by the mix bobbin, and is sufficiently 25 flexible to allow the activating material to pass around its edges.

The manner in which the cup is utilized is also an important feature of the invention. As illustrated in the drawing, it is 30 adapted to be attached to the lower end of the zinc tube in either of two positions, one of which corresponds with the inactive position and the other with the active position. In the construction illustrated in Figs. 1 35 and 2 this result is secured by forming a raised boss 14 at the lower end of the zinc tube, a vertical runway or groove 15 and two short substantially circumferential runways or grooves 16 and 17 connected thereto. 40 The cup is attached to the zinc tube in the inactive position by fitting the boss 14 in the upper end of runway 15 and then turning the cup so that the boss engages runway 16. When the cell is put into action the 45 cup is turned to draw the boss into runway 15 and the cup and zinc displaced by relative longitudinal adjustment to force the lower end of the mix bobbin against the seal 13 to release the paste. The latter will be slowly forced into the space between the 50 bobbin and zinc and when the boss reaches the runway 17 the cup will be turned to lock it to the end of the cell.

The construction also comprises a vent 18 55 in the seal, for permitting the air to escape while the paste is being displaced. The vent will be temporarily closed by pressing a little paraffine 18' therein. A coating of paraffine or other material 19 will usually be 60 provided at the junction of the cup and zinc

electrode to prevent evaporation. This substance will also serve to close the joint when the cup and zinc tube are subsequently telescoped to prevent leakage while the cell is 70 in use.

The modification of Figs. 3 and 4 resembles in general the structure of Figs. 1 and 2, but the essential differences will be discussed as they illustrate a modified method of securing results similar to those described. 75 A dry bobbin formed from a mix 20 of carbon and manganese dioxide with or without electrolyte salts, is molded around a carbon electrode 21. The bobbin thus formed is placed in a zinc tube 22, the mix 80 being spaced from the zinc and the space filled with a dry pervious material 22^a which may have electrolyte salts associated therewith. This material is more particularly described and claimed in United States 85 patent to R. C. Benner and H. F. French, No. 1,481,178, Jan. 15, 1924. When such materials are placed between the mix and the zinc electrode, these materials assist in keeping the bobbin centered in the zinc 90 electrode, especially when the cell is in inactive condition. For this reason if additional centering or spacing means are employed, they need not be so rigid as when the bobbin is otherwise unsupported. The 95 dry pervious filling material, if granular or powdered, is held in place by a disc of coherent and preferably pervious material 30. This latter disc readily permits the passage 100 of the activating liquid, which is usually quite fluid in this form of cell, by permeation or flexure or fracture of the disc. The activating material in this modification will be a liquid such as water or electrolyte solution, and its composition will depend upon 105 the composition of the pervious material and the mix.

In this modification a zinc tube threaded at the lower end 23 is shown which cooperates with a short threaded cup 24 containing the activating material which is retained by a seal 25 and insulating disc 25^a similar to those described in connection with the previous modification. A vent 26 at the top, and a paraffine coating 27 will be provided for the purpose referred to previously. The short screw threaded cup will be fastened to the zinc tube by screwing it thereon a short distance so that the zinc tube just touches the seal, and when the cell is to be used the liquid will be released by screwing the cup on the tube until the bobbin and disks are forced against the bottom of the cup as shown in Fig. 4. By means of the short screw threaded cup considerable pressure may be applied to force the activating material into the space provided therefor. 120

It is within the purview of the invention to utilize the screw threaded cup and tube 125 of the second modification with the paste 130

and other structural features of the first modification; or the construction of tube and cup of the first modification with the liquid and dry paste-forming materials of the second modification.

In each of the constructions the cup may be made of conducting or non-conducting materials. If metal cups, such as zinc, are used, these will preferably be provided with an internal waterproof coating 29 unaffected by the activating material. When non-conducting cups may be used the cups are provided with metallic bottoms fitted in the non-conducting side walls. In any of the modifications shown, when the bottom of the short cup containing the activating material is composed of metal, an additional disc of strawboard or the like 28 may be placed on such metal bottom as an extra safeguard against any fragments of the mix coming into contact therewith.

When the activating material is displaced by relative movement of the cup and bobbin, the zinc tube will be forced down into contact with the bottom of the cup or the materials resting thereupon. If it is desired to use the bottom of the cup as one of the terminals of the cell, as is usual in flashlight batteries, the bottom of the cell must of course be made of conducting material such as metal. In such a case the discs 12, 25^a and 28 are omitted or modified, and seals 13 and 25, and protective coating 29 if used, are made of fragile material such as paraffin, so that there will be no insulating material between the end of the zinc tube and the bottom of the cup except such as can readily be penetrated or broken by the end of the zinc tube. Electrical connection between the zinc tube and the conducting cup bottom will then readily be obtained by forcing these parts together.

Having described my invention, what I claim is:

1. A dry cell of the kind described, comprising a hollow zinc electrode, a depolarizing mix therein spaced therefrom, a carbon electrode in the mix projecting therefrom, a seal surrounding the projecting end of the carbon electrode, interlocking means between the seal and carbon electrode adapted to prevent displacement of the carbon electrode, a receptacle, a supply of activating material in the receptacle normally out of contact with the mix and adapted to be moved into contact therewith by longitudinal adjustment of the zinc and receptacle to activate the cell, said interlocking means being adapted to prevent displacement of the mix and to provide a passage free from localized obstructions for the activating material.

2. A dry cell of the kind described, comprising a hollow zinc electrode, a depolarizing mix therein spaced therefrom, a re-

ceptacle, a supply of activating material in the receptacle normally out of contact with the mix and adapted to be moved into contact therewith by relative adjustment of the zinc and receptacle to activate the cell, and 70 interlocking means between the seal and the zinc electrode adapted to prevent displacement of the mix and to provide a passage free from localized obstructions for the activating material.

3. A dry cell of the kind described, comprising a hollow zinc electrode, a depolarizing mix therein spaced therefrom, a carbon electrode in the mix projecting therefrom, a seal in the upper end of the zinc electrode 80 surrounding the projecting end of the carbon electrode, a receptacle, a supply of activating material in the receptacle normally out of contact with the mix and adapted to be moved into contact therewith by relative 85 longitudinal adjustment of the zinc electrode and receptacle to activate the cell, interlocking means between the zinc and the seal and interlocking means between the carbon electrode and the seal, said interlocking means being adapted to prevent displacement of the mix and to provide a passage 90 free from localized obstructions for the activating material.

4. A dry cell of the kind described, comprising a hollow zinc electrode, a depolarizing mix therein spaced therefrom, a carbon electrode in the mix having an end projecting therefrom, a seal in the upper end of the zinc surrounding the projecting end of the carbon electrode, said carbon electrode having a plurality of interlocking irregularities in its surface adjoining the mix and seal adapted to retain the mix and prevent displacement of the carbon in the seal, a receptacle, a supply of activating material in the receptacle normally out of contact with the mix and adapted to be moved into contact therewith by relative longitudinal adjustment of the zinc and receptacle to activate 105 the cell, said carbon and interlocking mix and seal being adapted to space the mix from the zinc and to prevent displacement thereof and to provide a passage free from localized obstructions for the activating material. 110

5. A dry cell of the kind described, comprising a tubular zinc electrode, a depolarizing mix, a carbon electrode in the mix having an end projecting therefrom, a seal in the upper end of the zinc electrode and surrounding the projecting end of the carbon electrode, said carbon electrode having irregularities in the surface thereof adapted to interlock with the mix and seal, and said tubular zinc electrode having a flange there- 120 in projecting into the seal, a receptacle, a supply of activating material in the receptacle normally out of contact with the mix and adapted to be moved into contact therewith by relative longitudinal adjustment of the 125

- zinc electrode and receptacle to activate the cell, said flange between the zinc electrode and seal and irregularities in the carbon electrode being adapted to prevent displacement 5 of the mix whereby a passage free from localized obstructions is provided for the activating material.
6. A dry cell of the kind described, comprising a tubular zinc electrode, a depolarizing mix therein spaced therefrom, a cup attached to the lower end of the zinc tube, a supply of activating material in the cup normally out of contact with the mix and adapted to be moved into contact therewith by 10 relative longitudinal adjustment of the cup on the tube to activate the cell, and means adapted to provide an air-tight seal between the cup and tube in both the active and inactive positions.
- 15 7. A dry cell of the kind described, comprising a hollow zinc electrode, a depolarizing mix bobbin therein spaced therefrom, a cup attached to the lower end of the hollow electrode, a coating of waterproof material 20 on the inside of the cup and a supply of activating material in the cup normally out of contact with the mix and adapted to be moved into contact therewith by collapsing the cup and hollow zinc electrode.
- 25 8. A dry cell of the kind described, comprising a hollow zinc electrode, a depolarizing mix therein spaced therefrom, a cup, a boss on the lower end of said zinc and cooperating grooves on the cup, said grooves
- and boss being adapted to retain the cup on the end of the tube in two positions corresponding with the active and inactive conditions of the cell, a supply of activating material in the cup normally out of contact with the mix in one of said positions and 30 adapted to be moved into contact therewith by longitudinal adjustment of the zinc and cup.
- 35 9. A dry cell of the kind described, comprising a zinc electrode, a depolarizing mix 40 therein spaced therefrom, a permeable mass between the mix and zinc electrode, a receptacle, a supply of activating material in the receptacle normally out of contact with the mix and permeable mass and adapted to be 45 moved into contact with the mix and permeable mass by relative longitudinal adjustment of the zinc and receptacle to activate the cell.
- 45 10. A dry cell of the kind described, comprising a tubular zinc electrode, a depolarizing mix therein spaced therefrom, a permeable mass between the mix and zinc tube, a cup adapted to be attached to the lower 50 end of the zinc tube and a supply of liquid in said cup normally out of contact with the mix and permeable mass and adapted to be moved into contact therewith by relative longitudinal adjustment of the tube and cup to activate the cell. 55

In testimony whereof, I affix my signature.

RAYMOND C. BENNER.
